UNITED STATES PATENT OFFICE.

ABRAM B. LAWRENCE, OF WARSAW, NEW YORK.

DESIGN FOR BURIAL-CASKET.

Specification forming part of Design No. 6,145, dated September 17, 1872.

To all whom it may concern:

Be it known that I, ABRAM B. LAWRENCE, of Warsaw, in the county of Wyoming and State of New York, have invented a new and original Design for a Coffin or Casket, of which the following is a specification:

In the accompanying drawing, Figure 1 represents a perspective view of my new design for a coffin. Fig. 2 is a detail vertical transverse section of the same.

Similar letters of reference indicate corresponding parts.

This invention relates to a new manner of ornamenting the ends and sides of coffins and burial-caskets by means of countersunk or grooved panel-borders. The invention consists, first, in the new configuration of the panels at the sides of the coffin, which are formed by straight upper and lower lines and

by vertical lines at the ends, and have intermediate crosses, as shown. All these lines are grooved, as indicated in Fig. 2. Each end of the coffin contains a plain panel, whose lines are parallel with the edges of the end pieces, and also grooved.

The grooves I propose to paint black, in imitation of ebony, thereby producing a beautiful effect on the rose-wood, mahogany, or other wood of which the coffin is constructed.

I claim as my invention—

1. The design for the ebony imitation grooved end panels of a coffin or burial-case, as shown.
2. The design of an ebony imitation side panel for coffins or caskets, as shown.

ABRAM B. LAWRENCE.
